[57] CLAIM

The ornamental design for a chair base, as shown and described.

DESCRIPTION

FIG. 1 is a perspective view of a chair base, showing my new design;

FIG. 2 is a top plan view;

FIG. 3 is a bottom plan view;

FIG. 4 is a side elevational view;

FIG. 5 is an alternate side elevational view;

FIG. 6 is an elevational view, showing the side not shown in FIG. 4;

FIG. 7 is a perspective view of a chair base, showing an alternate embodiment of my new design;

FIG. 8 is a top plan view of the alternate embodiment; FIG. 9 is a bottom plan view of the alternate embodiment; and

FIG. 10 is a side elevational view of the alternate embodiment, showing one of four identical sides.

FIG. 1

FIG. 2

FIG. 3

FIG. 4

FIG. 5

FIG. 6
